UNITED STATES PATENT OFFICE.

WILLIAM McGALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 14,267, dated September 11, 1883.

Application filed August 3, 1883. Term of patent 3½ years.

To all whom it may concern:

Be it known that I, WILLIAM McCALLUM, of Yonkers, in the county of Westchester and State of New York, have invented and produced a new and original Design for a Carpet, of which the following is a full description, in connection with the accompanying photograph, which represents a face view of my new design for a carpet.

10 This invention relates to a new configuration of groups by which the body of a carpet or analogous fabric is decorated.

At the upper and lower parts of the photograph are shown groups A A of conventional flowers, which are placed in a field that is in part embraced by a scroll, B, in an angle of which is the conventional leaf a. From the scroll B extends the scroll C, which embraces the acorn-like figure b, and which, by the quadrangular dotted border d, connects with the scroll B, as shown. This border d is partly overlapped by rosette-like figures e. At the left of the scroll B is the floral ornament f, and above that the floral ornament g, that appears to grow out of the rosettes e. Above these rosettes is a fanciful scroll, D, containing the stem of a twig, E, which extends into a field, F, of irregular outline. At the right of the scroll D is the group h of leaves and clusters of fruit, above which is the bracket-like figure G. Above the field F is an angular field, H, out of which the floral decoration A appears to emanate, and at the left of this figure H is the scroll I, which embraces a group of flowers and leaves, i.

35 The entire design, taken as a whole, has an oriental effect, and appears very fanciful and rich to the eye.

I claim—

The design for a carpet, the same consisting 40 of the figures A B C D E F G H I a b d e f g h i, substantially as shown.

WILLIAM McCALLUM.
